UNITED STATES PATENT OFFICE.

CHARLES KLEPPER, OF SAN FRANCISCO, CALIFORNIA.

HAIR-DRESSING FRAME.

1,237,792.

Specification of Letters Patent. Patented Aug. 21, 1917.

Application filed January 26, 1916. Serial No. 74,398.

To all whom it may concern:

Be it known that I, CHARLES KLEPPER, a citizen of the United States, residing at San Francisco, in the county of San Francisco 5 and State of California, have invented certain new and useful Improvements in Hair-Dressing Frames; and I do hereby declare the following to be a full, clear, and exact description of the invention, such as will 10 enable others skilled in the art to which it appertains to make and use the same.

This invention has for its primary object to provide an efficient and inexpensive hair dressing frame or foundation particularly 15 designed for use in dressing ladies' hair and permitting of a thorough circulation of air beneath the coils of the hair placed upon the crown or back of the head.

With this and other objects in view, the 20 invention consists in the novel construction, combination and arrangement of parts as will be hereinafter specifically described, claimed and illustrated in the accompanying drawing, in which:

25 Figure 1 represents a perspective view of the hair dressing frame, and

Fig. 2 represents an enlarged fragmental front elevation thereof.

Referring to the drawing in detail, where- 30 in similar reference numerals designate corresponding parts throughout the several views, the numeral 5 indicates generally the base loop of the hair frame, the free ends of which are movable relatively and connected by a loop 8 consisting of two side members which are bowed or curved in such 35 manner that they are crossed, as clearly illustrated in Fig. 1, when the free ends of the main or base loop 5 are connected.

40 Adjacent the point of juncture of one side of the loop 8 with the adjacent end of the main or base loop 5 the wire or other material from which the hair dressing form is constructed is bent to define a substan- 45 tially U-shaped retaining loop 10 adapted to receive the other side member of the loop 8, whereby the free ends of the base loop are detachably connected. The base loop 5 is formed of resilient material so as 50 to normally retain the free ends thereof sprung apart, and thus when one side member of the loop 8 is engaged under the re-

taining loop 10 the band is resiliently re- tained in contracted condition.

The curved bracing member 6 is secured 55 at diametrically opposed points to the base loop 5 between the free ends and central portion of the latter, and the central portion thereof is looped, as indicated at 6^a, about the looped inner end 9 of an auxiliary 60 bracing member 7, which latter is an ex- tended part of the wire, or other material forming the base loop 5, and is designed to reinforce the brace 6 and retain the latter in a predetermined position with relation to 65 the base loop 5. The looped end 9 of the auxiliary bracing member receives and an- chors the closed end of the loop 8. The ex- treme inner end of the auxiliary bracing member 7 is turned back upon the coiled 70 portion 6^a of the curved member 6, as indi- cated at 7^a, thereby forming a rigid connec- tion between the members 6 and 7.

In use, the hair dressing frame is placed 75 in any desired position upon the head of the wearer and the strands of hair are posi- tioned through the loop 8 and the ends of base loop 5 are subsequently connected by engaging the bight portion 11 at one end thereof in the loop 10 at the opposite end. 80 The frictional engagement of the sides of the loop 8 prevent accidental displacement of the hair dressing frame while the hair is being dressed, and, as will be understood, the frame is entirely concealed from view by the 85 coils of hair placed thereon, while at the same time the coiled hair is retained in spaced relation to the scalp of the wearer and insuring proper circulation of air about the scalp.

90 What is claimed is:

In a hair dressing frame, a base loop of semi-circular sections having certain of the ends twisted together, a hair-receiving loop connecting the other ends of the base loop, 95 means detachably connecting the free ends of the base and hair-receiving loops, a curved bracing member connected at its op- posite ends with the base loop, an auxiliary bracing member integrally connected at one 100 end to said base loop, a loop integrally connected with the inner extremity of the auxiliary bracing member receiving and an- choring the hair-receiving loop, and a loop

formed centrally of the curved bracing member receiving and closing the loop of the auxiliary bracing member, said auxiliary bracing member having its extreme end 5 turned back over the loop of the curved bracing member to rigidly connect the two bracing members.

In testimony whereof I affix my signature in presence of two witnesses.

CHARLES KLEPPER.
